UNITED STATES PATENT OFFICE.

HARRY E. BAYLY, OF INDIANAPOLIS, INDIANA, ASSIGNOR OF ONE-HALF
TO WILLIAM S. HOLCOMBE, OF BEDFORD, INDIANA.

TELESCOPING MECHANISM.

SPECIFICATION forming part of Letters Patent No. 770,550, dated September 20, 1904.

Application filed September 8, 1903. Serial No. 172,228. (No model.)

To all whom it may concern:

Be it known that I, HARRY E. BAYLY, of Indianapolis, county of Marion, and State of Indiana, have invented a certain new and useful 5 Telescoping Mechanism; and I do hereby declare that the following is a full, clear, and exact description thereof, reference being had to the accompanying drawings, in which like numerals refer to like parts.

10 The object of this invention is to provide means for telescoping each of a plurality of members with an equal and simultaneous movement. For example, the invention may be applied and I have herein shown it applied 15 to a pneumatic straw-stacker consisting of three tubes, one stationary and the other two telescoping on the stationary tube. With my telescoping mechanism connected with said sections each of the movable sections will be 20 moved simultaneously and to an equal extent.

The full nature of this invention will be understood from the accompanying drawings and the following description and claims.

In the drawings, Figure 1 is an elevation of 25 the right-hand side of a pneumatic straw-stacker tube with my telescoping mechanism thereon, the tube being shown closed. Fig. 2 is the same with the tube extended. Fig. 3 is a transverse section on the line 3 3 of Fig. 30 1. Fig. 4 is a central vertical section through the upper part of the tube-sections and the telescoping mechanism, parts in side elevation and parts broken away.

The pneumatic tube herein shown consists 35 of a stationary section 10, a middle movable section 11, and an extreme or end movable section 12. The section 11 telescopes on the section 10, and the section 12 telescopes on the section 11.

40 The telescoping mechanism consists in the form shown herein of a small tube 15, parallel with the members 10, 11, and 12 of the main tube and mounted above them to serve as means for guiding the telescoping movement 45 of the movable sections 11 and 12. Said tube 15 is secured stationary at one end to a bracket 16, which is fastened on the stationary section 10. Its outer end is open, and it extends as far or slightly farther than the limit of

movement of the inner end of the middle movable section 11. A second small tube 17 telescopes within the tube 15, as seen in Fig. 4, and is closed at its outer end. At its inner end it is secured to the middle section 11 by a connecting-bracket 18, that extends through 50 a vertical slot in the lower side of the small tube 15. A short sliding tube 20 slides longitudinally within the inner tube 17 and is connected with the end of the movable section 12 by the bracket 21, which extends through 55 the longitudinal slots in the lower sides of both the tubes 15 and 17.

The middle section 11 is moved by the sprocket-chain 23, operated by the crank 24, mounted on the bracket 16 on the stationary 60 section 10. The other end of the sprocket-chain runs over a sprocket-wheel 25, mounted on one side of the small tube 15, and the middle section 11 is secured to said chain between its ends by the bracket 26. When the chain 65 is operated, the section 11 will be telescoped to and fro.

In order that the section 12 will move at the same time and away from the section 11 with the same speed that the section 11 moves away 70 from the section 10, I have provided the following mechanism: The pulley 30 is mounted within the tube 17 near its extreme end, and another pulley, 31, is mounted in the other end of the same tube. A cable or cord 32 extends 75 about said pulleys and is secured on one side at 33 to the bracket 21 from the movable section 12, and at the other side it is also held in some stationary way, the means shown being the end of a very small tube 34, through 80 which the cable or cord extends. The small tube 34 is secured within the stationary tube 15, and the cord or cable 32 passes through said small tube to the inner end of the stationary tube, where it is tied. The means described successfully hold the cable at the outer 85 end of the tube 34 and is a convenient means for use when the small tubes 15 and 17 are used. The purpose is that the cable or cord 32 shall be held stationary at a point between 90 the limit of movement of the pulleys 30 and 31. It is obvious that with the cable thus held and mounted the section 12 will be moved 95

from section 10 twice as fast as the section 11, and with said sections of equal length they will reach their limit of movement at the same time whether they be moved outward or inward.

I do not wish to limit the invention to tubular guides, like 15 and 17, or to any particular means for holding one side of the cable 32 stationary, as those parts can readily be modified. What is necessary to the operation of the device according to the invention herein set forth is means for longitudinally guiding the sections having some telescoping guide, like 17, that moves with the middle section, and having on it pulleys, like 30 and 31, and a cable, like 32, and having said cable fastened on one side to the movable section 12 and on the other side to the stationary means between the pulleys 30 and 31; nor do I wish to be limited to a construction with only two movable tubes, as the number might be increased by merely duplicating the parts; nor do I wish to be limited to telescoping tubes, as extension-ladders or similar constructions might be extended by the same telescoping mechanism as would telescope tubes. By "telescoping" I mean in this specification and the claims the movement of two or more members either in each, as in case of a telescope, or on each other, as in case of an extension-ladder or the like. It is seen that the outer member in the main tube moves at the same time and to the same extent as the inner member, and the movement of said outer member is automatic.

What I claim as my invention, and desire to secure by Letters Patent, is—

1. The combination with three telescoping members, one of which is stationary and the others movable, of means carried by the middle member for guiding the movement of said movable members and distinct from the movable members, means for moving the middle member, and means controlled by the movement of the middle member for telescoping the outer member simultaneously with the movement of said middle member.

2. The combination with three telescoping members, one of which is stationary and the others movable, of a sliding means for guiding said members that is secured to the

middle member, a pulley mounted near each end of said sliding guide, a cable extending about said pulleys that is on one side secured stationary and at the other side is secured to the outer movable member, and means for moving the middle member.

3. The combination with three members, one of which is stationary and the other two telescoping, of a parallel guide secured to said stationary member for guiding the movement of the middle member, a guide slidably mounted in connection with said stationary guide for guiding the outer movable member and which is connected with the middle member, means mounted in connection with said stationary guide for moving said middle member, a pulley near each end of the movable guide, and a cable extending about said pulleys and secured stationary at one side and at the other side secured to said outer movable member.

4. The combination with a stationary member and two members telescoping thereon, of a parallel guiding-tube mounted on said stationary member with a longitudinal slot along the side thereof and adjacent said telescoping members, a tube for guiding the movement of said outer member that telescopes within said stationary guiding-tube and has a longitudinal slot to register with the slot in the stationary guiding-tube and secured to said outer member, a bracket extending from the outer movable member through the slots in said tubular guides and slidably within said movable guides, a pulley mounted within said movable guiding-tube near each end, a small tube secured within said stationary guiding-tube and extending through it and the movable guiding-tube to a point between the limits of movement of said pulleys, and a cable secured within said small tube and extending through it and about said pulleys and secured to the bracket extending from said outer movable member, substantially as shown and described.

In witness whereof I have hereunto affixed my signature in the presence of the witnesses herein named.

HARRY E. BAYLY.
